UNITED STATES PATENT OFFICE.

HENRY J. DAVIES, OF BROOKLYN, NEW YORK.

DESIGN FOR A CLOCK-STAND.

SPECIFICATION forming part of Design No. 12,562, dated November 1, 1881.

Application filed September 21, 1881. Term of patent 7 years.

To all whom it may concern:

Be it known that I, HENRY J. DAVIES, of Brooklyn, in the county of Kings and State of New York, have originated and produced an 5 Improved Design for Clock-Stands, of which the following is a specification.

The character of my design is clearly shown in the accompanying drawing, which represents a front elevation of a clock-stand embodying the design.

A designates the base of the clock-stand, which is made in the form of a truncated pyramid, with fillets *a* *b* at its bottom and top, and a fillet, *c*, intermediate between its top and bottom. The base is supported at the corners upon feet *B*, the corners of which form approximately continuations of the corners of the base. *A*. The feet are composed of foliated open-work, and only one of them is here shown complete, the other front foot being shown simply in outline. The portion of the base between the fillets *a* and *c* is ornamented by a row of pointed arches, *d*, in relief, each arch containing a flower-like ornament, *d'*, and between the arches are flower or leaf like ornaments *d''*. The portion of the base between the fillets *b* *c* is ornamented by a row of ellipses, *e*, each containing a Maltese cross, *e'*, and surrounded by a scalloped border, *e''*, from which leaf-like ornaments project. The ornamentation on the base *A* is not shown entirely across the length thereof; but it will be understood that it extends entirely across from side to side.

At the front corners of the stand are columns, *C*, having molded bases *C'* and beads *f*, above which are finials *D*, slightly curved outward.

E designates the clock-case, which is of circular form, and below this case and between the columns *C* is a front plate, *F*, upon which is the representation of a spray of flowers, *g*, and a bird, *h*.

The case *E* is surmounted by an arched top, *G*, composed of two arc-shaped bars, *i* *i'*, united at their ends by curved bars *i''* and resting upon the finials *D*. The space between the bars

i *i'* is filled up by a foliated ornamentation, *j*, which is here only shown upon one-half the top *G*, and said top is surmounted by a finial ornament, *G'*.

What I claim, and desire to secure by Letters Patent, is—

1. The design for a clock-stand, comprising the pyramidal base *A*, the columns *C*, and the arched top *G*, as shown and described.

2. The ornamentation for the base of a clock-stand, consisting of the pointed arches *d* and flower-like ornaments *d'* in said arches, as shown and described.

3. The ornamentation for the base of a clock-stand, consisting of the ellipses *e* and Maltese crosses *e'*, contained therein, as shown and described.

4. The design for the base of a clock-stand, comprising the pyramidal base *A*, ornamented by a row of ellipses, *e*, and Maltese crosses *e'*, and a row of arches, *d*, and the foliated ornamental feet *B*, as shown and described.

5. The design for a clock-stand, comprising columns *C*, the surmounting outwardly-curved finials *D*, the arched top *G*, composed of arc-shaped bars *i* *i'* and intermediate foliated ornamentation *j*, and the finial *G'*, as shown and described.

6. The design for a clock-stand, comprising the columns *C*, the outwardly-curved finials *D*, the arched top *G*, the circular case *E*, and the spray of flowers *g* and bird *h*, as shown and described.

7. The design for a clock-case, comprising the pyramidal base *A*, with arches *d* and ellipses and Maltese crosses *e* *e'*, the foliated feet *B*, the columns *C*, and outwardly-curved finials *D*, the circular case *E*, the spray of flowers and bird *g* *h*, the arched top *G*, composed of bars *i* *i'* and foliated ornamentation *j*, and the finial *G'*, as shown and described.

HENRY J. DAVIES.
